SKIRT HANGER

Hollace Dale Wischart and Dellis Lewis Wischart,
Trail, Minn.

Application November 24, 1937, Serial No. 176,336

5 Claims. (Cl. 223—91)

This invention relates to an improved skirt hanger especially adapted for use in conjunction with conventional wire coat hangers of the kind at present so widely in vogue.

5 An object of the invention is to provide a skirt hanger which will adapt the conventional wire hanger mentioned to the dual purpose of supporting a coat and, at the same time, also supporting a skirt so that the shape and neat appearance of both will be restored and preserved.

Another object of the invention is to provide a skirt hanger which may be readily attached to a conventional wire coat hanger or as easily detached therefrom, and which will be simple, efficient and compact so that should a person so desire, a pair of the devices may be carried in a purse, for instance, and applied for use as occasion may demand.

20 A further object of the invention is to provide a skirt hanger which may be readily adjusted along the bottom bar of the coat hanger to suit the width of a skirt at the waist band thereof, so that the device will thus be adapted for a wide range of use, and wherein the resiliency of the 25 bottom bar of the coat hanger will be utilized to maintain the waist band more or less taut and thus not only tend to free the skirt of wrinkles but also tend to maintain the hanger engaged with the waist band.

30 Still another object of the invention is to provide a skirt hanger embodying a coil adapted to be screwed onto the bottom bar of the coat hanger for attaching the skirt hanger thereto, but wherein said coil will be composed of few turns of 35 steep pitch to thus provide, notwithstanding the small number of turns, an elongated sleeve normally connecting the hanger slidably with said bar to move easily therealong while, when the skirt hanger is tilted by the weight of a skirt 40 thereon, the canting pressure on the coil will be concentrated at the small area presented by a few turns only, to thus afford a correspondingly effective frictional grip of the coil on said bar for maintaining the hanger in adjusted position supporting the skirt.

45 And the invention seeks, as a still further object, to provide a skirt hanger equipped at its outer end with a novel spring clamp with which the waist band of a skirt may be readily engaged, and wherein a clamping button will be provided and so mounted that the weight of the skirt will 50 constantly tend to shift the button in a direction to bind the button more tightly in engagement with the waist band for effectually securing the 55 skirt upon the hanger.

Other and incidental objects of the invention will appear during the course of the following description and in the accompanying drawing.

Figure 1 is a perspective view showing our improved hanger in conjunction with a conventional wire coat hanger, a portion of a skirt being illustrated in dotted lines.

Figure 2 is a detail perspective view showing the hanger detached.

Figure 3 is a fragmentary perspective view showing a slight variation of the invention.

Figure 4 is a fragmentary perspective view showing another slight variation of the invention.

Referring now more particularly to Figures 1 and 2 of the drawing, it will be seen that our 15 improved device comprises a long arm 10 and a somewhat shorter arm 11, the two arms standing at a slightly obtuse angle with respect to each other. The device is preferably formed from a length of relatively stiff resilient wire of suitable gauge and at the free end of the arm 10, the wire is twisted to provide an open helical coil 12 terminating in a curved free tip 13. As will be observed, the coil preferably comprises only a few turns, two turns being shown in the 25 present instance.

At the free end of the arm 11, the wire is looped upwardly or, in other words, in the direction of the arm 10 to form an inverted substantially U-shaped clamp 14, one jaw 15 of which inclines toward the arm 11 to abut thereagainst near its upper end while the other jaw 16 of said clamp inclines downwardly toward the lower end of the jaw 15 to provide a reduced throat between the jaws at the lower end of the clamp, the jaw 16 terminating in an eye 17. Freely slidable on the jaw 16 is a clamping button 18 which may be of any suitable material and is limited against displacement by the eye 17.

40 In order to better bring out the mounting and use of our improved skirt hanger, we have shown the device in conjunction with a conventional resilient wire coat hanger embodying the usual hook 19, sides 20 and bottom bar 21. To attach the present device, the arm 10, as suggested in 45 Figure 2 of the drawing, is disposed in alignment with the bottom bar 21, when the tip 13 of the coil 12 is engaged about the adjacent end of the bar. By then rotating the device, the coil 12 will be screwed onto said bar to engage thereabout, 50 connecting the device with the coat hanger.

It is now to be observed that the coil 12 is of a diameter to somewhat loosely receive the bar 21 of the coat hanger so that, as shown in Figure 1, the device may cant relative to the bar. Fur- 55

thermore, it is to be noted that the pitch of the coil is extremely steep so that notwithstanding the fact the coil comprises only two complete turns, the coil is nevertheless, of sufficient length 5 to form an elongated sleeve slidably mounting the skirt hanger so that by disposing the arm 10 in parallel relation to the bar 21, the device may then be freely adjusted along said bar.

In practice, a pair of the devices is mounted 10 upon the coat hanger, as shown in Figure 1, and, as will now be perceived, by adjusting the skirt hangers along the bar to the proper position, the waist band of a skirt, as conventionally shown in dotted lines at 22, may be readily slid upwardly into the clamps 14 when, by spreading the skirt hangers, the waist band will be drawn taut while also, the skirt hangers will be canted downwardly. Thus, the coils 12 will be caused to frictionally grip the bar 21 and, of course, upon 15 the release of the skirt by the operator, the weight of the skirt will serve to maintain the skirt hangers canted and urge the coils 12 into binding engagement with the bar 21. For such reason, the arms 10 of the hangers are longer than 20 the arms 11, since, as will now be seen, when a skirt is engaged with the hangers, the arms 10 will serve as levers acting under the weight of 25 the skirt to cant the coils 12 with augmented force into engagement with the bar 21 so that slipping 30 of the skirt hangers will be effectually forestalled. As will be appreciated, the clamps 14 will provide handles which may be conveniently grasped between the thumb and forefinger for adjusting the skirt hangers relative to each other.

35 After the waist band of the skirt has been engaged in the clamps 14, as previously described, the buttons 18 are manually shifted downwardly along the jaws 16 to wedge against the waist band and thus tension said jaws to resiliently hold the 40 buttons engaged with the waist band. Furthermore, any tendency of the waist band to slip downwardly, under the weight of the skirt, will tend to shift the buttons further downwardly on the jaws 16 and thus increase the tension of the 45 jaws on the buttons so that the skirt will be securely held on the hangers. Also, in this connection, it is to be noted that due to the upward inclination of the jaws 15, the loops at the lower ends of said jaws provide humps 23 over 50 which the waist band of the skirt extends. Thus, the distance between the humps 23 of the two hangers is greater than the distance between the upper ends of the jaws 15 of said hangers so that the waist band, after being drawn taut between 55 the hangers, cannot ride over the humps 23 to become accidentally released.

As will be appreciated, tension on the waist band of the skirt 22 will not only tend to eliminate wrinkles about the waist of the skirt but will also tend to cause the coils 12 to grip the bar 21 more solidly to obviate slipping and by slightly bowing the bar 21 upwardly at the time the skirt is engaged with the skirt hangers, the resiliency of said bar may be utilized to augment 60 the canting action of the skirt on said coils. As will be perceived, the bowed bar 21 will, upon the release thereof, tend to straighten and thus resiliently urge the clamps 14 of the two hangers apart against the limiting action of the waist 65 band of the skirt, thus tending to further cant the arms 10 of the hangers with consequent increased gripping of the coils on the bar 21.

The coils 12 each comprise only a few turns, as stated, so that the canting pressure on the coils 70 will be concentrated in the correspondingly 75

limited area presented to the bar 21 by such small number of turns. Experiment has shown that when a large number of turns are used, the canting pressure is distributed between the turns with the result that no one turn is caused to frictionally bite the bar 21 effectually. In contrast, by using only two complete turns in each coil, the canting pressure is intensified in the small areas in effective contact with the bar so that the frictional grip of the coils on the bar is correspondingly more pronounced and slipping prevented. 10

In Figure 3 of the drawing we have shown a slight variation of the invention wherein the coil 12a of the skirt hanger is provided with a terminal eye 24 permanently connecting the hanger with the bar 21 of the coat hanger. A pair of the skirt hangers will, of course, be employed. 15

In Figure 4 we have shown another slight variation wherein the bottom bar 21a of the coat hanger is bent at each end to provide a depending stop loop 25. As will be perceived, these loops will prevent removal of a pair of the skirt hangers from the bar. Otherwise, the variations shown in Figure 3 and 4 of the drawing are identical with 25 the construction first described and the same reference numerals have accordingly been applied to like parts throughout.

Having thus described our invention, we 30 claim:

1. A skirt hanger including angularly disposed arms one terminating in a helical coil of few turns but steep pitch to provide an elongated gripping sleeve of a diameter to loosely receive the bottom bar of a coat hanger for slidably connecting the skirt hanger with said bar, and the other of said arms terminating in a skirt engaging clamp, the coil being movable to cant and frictionally grip said bar under the weight of a skirt engaged with said clamp. 35

2. A skirt hanger including angularly disposed arms one terminating in a helical coil of few turns but steep pitch and open at its free end to wind about the bottom bar of a coat hanger as the coil is rotated for connecting the coil with 45 said bar, and the other of said arms terminating in a skirt engaging clamp, the coil being of a diameter to loosely receive said bar for slidably connecting the skirt hanger therewith and being movable to cant and frictionally grip the bar 50 under the weight of a skirt engaged with said clamp.

3. A skirt hanger formed from a length of wire bent to provide angularly disposed arms one longer than the other and twisted to form an elongated helical coil of few turns but steep pitch to provide an elongated gripping sleeve of a diameter to loosely receive the bottom bar of a coat hanger for slidably connecting the skirt hanger with said bar, and the wire being looped 60 at the lower end of the other of said arms to form an inverted substantially U-shaped skirt engaging clamp having downwardly converging jaws one of which is free, and a clamping button 65 slideable on said free jaw, the coil being movable to cant and frictionally grip said bar under the weight of a skirt disposed between the jaws of said clamp and engaged by said button.

4. A skirt hanger including angularly disposed arms one terminating in a helical coil of few 70 turns but steep pitch to provide an elongated gripping sleeve of a diameter to loosely receive the bottom bar of a coat hanger for slidably connecting the skirt hanger with said bar and terminating in an eye limiting the skirt hanger 75

against removal from said bar, and the other of said arms terminating in a skirt engaging clamp, the coil being movable to cant and frictionally grip said bar under the weight of a skirt engaged 5 with said clamp.

5. The combination with a coat hanger having a bottom bar, of a skirt hanger having angularly disposed arms one terminating in a helical coil of few turns but steep pitch to provide an elongated 10 gripping sleeve loosely receiving said bar to slid-

ably connect the skirt hanger therewith, the bar being formed at its ends with stop loops limiting the coil against removal from said bar, and the other of said arms terminating in a skirt engaging clamp, the coil being movable to cant and frictionally grip said bar under the weight of a skirt engaged with said clamp. 5
